UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL COMPOSING MACHINE.

1,406,563.

Specification of Letters Patent. Patented Feb. 14, 1922.

Original application filed July 3, 1920, Serial No. 393,856. Divided and this application filed June 16, 1921. Serial No. 478,217.

To all whom it may concern:

Be it known that I, DAVID S. KENNEDY, a citizen of the United States, residing at Brooklyn, in the county of Kings and State of New York, have invented certain new and useful Improvements in Typographical Composing Machines, of which the following is a specification, reference being had therein to the accompanying drawing, and a 10 division of an application filed by me July 3, 1920, Serial No. 393,856.

My invention relates to typographical machines, such as linotype machines of the general organization represented in Mergenthaler Patent No. 436,532, wherein circulating matrices are released from a magazine by the manipulation of a keyboard in the order in which their characters are to appear in print and then assembled in line, the composed line transferred to the face of a mold, the mold filled with molten metal to form a slug or linotype against the matrices which produce the type characters thereon, and the matrices thereafter elevated and returned 25 through a distributing mechanism to the magazine from which they started.

My present improvements are directed to an automatic arrangement for locking the keyboard when the operation of the machine 30 is arrested or, more specifically, when the power is shut off, a feature which is very desirable in guarding against the accidental or unintentional actuation of the finger keys at an improper time. The arrangement is 35 also such that the keyboard will be automatically unlocked when the operation of the machine is subsequently resumed, so as thus to release the finger keys for proper manipulation.

40 In the accompanying drawings, I have shown my invention merely in preferred form and by way of example and as applied to a machine of the class stated, but obviously many changes and alterations may 45 be made therein and in its mode of operation which will still be comprised within its spirit. Generally speaking, I desire it to be understood that I do not limit myself to any specific form or embodiment except in 50 so far as such limitations are specified in the claims.

Referring to the drawings:

Fig. 1 is a side elevation of a portion of a

linotype machine having my invention embodied therein; and

Fig. 2 is a front view of a detached portion of the automatic adjusting connections represented in Fig. 1.

I have herein illustrated only such parts of the machine as are immediately concerned with my present invention. The other parts may be of any well-known construction, such for example as presented in the commercial linotype machine, or as illustrated in the Mergenthaler patent before mentioned.

The keyboard is of standard construction comprising the supporting frame A and the series of horizontal finger keys or key levers B pivotally mounted therein for vertical movement upon the transverse rods A¹ which sustain them in rows at different levels in the customary way. The finger keys are guided in their vertical movements by the front plate A² fixed to the supporting frame A and formed with elongated slots wherein the forward ends of the finger keys are arranged, it being understood of course that the extent of the slots is such as to permit the required actuating movement of the finger keys. At their rear ends the finger keys are engaged with vertically movable slides connected at their upper ends to trip dogs controlling the operation of pivoted cam yokes which, by the engagement of their cams with underlying power driven rolls, are rocked upwardly to operate the matrix releasing devices. These details are well understood in the art, but if desired reference may be had to the Dodge Patent No. 530,931 for further particulars.

The various power driven parts of the machine are all operated from the electric motor G, the driving connections being made through the small pinion G¹ fixed to the armature shaft and the large gear G², mounted on the main cam shaft. This gear G² is connected to the keyboard rolls before mentioned through the customary belt and pulley arrangement. The electrical connections G³ for the motor include the switch button G⁴ arranged at the front of the machine within easy reach of the operator and which is adapted to be given quarter rotations in turning on or shutting off the current.

As before stated, the present invention is directed to an automatic arrangement whereby the keyboard is locked or unlocked according to whether the machine is in use or 5 out of use. Stated more specifically, the keyboard is equipped with a suitable locking device which is automatically moved to active and inactive position as the motor is stopped and started, respectively.

10 In carrying out my invention, I propose to make use of the improved locking device presented in the parent application Serial No. 393,856, before referred to. This locking device is in the form of a plate C 15 ably mounted upon the fixed front plate A² and formed with elongated slots through which the forward ends of the finger keys B extend, the plate C thus being practically a duplicate of the plate A². It will be seen, 20 therefore, that by adjusting the plate C backwardly and forwardly upon the fixed plate A², the finger keys B may be locked or unlocked as desired. Thus, in the forward or inactive position of the locking plate C, its elongated slots are in registry 25 with the corresponding slots of the fixed plate A², so that the finger keys are free to be depressed or actuated in the usual way; but when the locking plate is in its rearward 30 or active position, its slots are out of registry with those of the fixed plate and present their lower end walls beneath and in engagement with the bottom edges of the finger keys, which are thus locked against 35 depression or actuation, all as fully set forth in said parent application. In providing for the automatic adjustment of the locking plate C, connections are provided between it and the switch button G⁴. This switch button G⁴ is provided with a cam plate H, 40 presenting alternate depressions and elevations h and h¹, respectively, and arranged to co-operate with a roller H¹ journaled in the lower end of a vertically movable rod H², 45 which is suitably guided in a bracket O and constantly urged downward by a spring H³ to maintain the roller and cam-plate in engagement. At its upper end, the rod H² is connected to a horizontal arm H⁴ fixed to 50 one end of a transverse rock shaft H⁵ journaled in the bracket O and provided at its opposite end with a vertical arm H⁶, which latter is connected by a forwardly extending link H⁷ to the lower end of a lever H⁸ centrally pivoted to a second bracket O¹ and 55 in turn connected at its upper end by a pin-and-slot device H⁹ to the locking plate C.

According to the above arrangement, when the switch-button G⁴ is turned "on" to 60 start the operation of the motor G, the cam plate H presents one of its depressions h in engagement with the roller H¹ and hence permits the spring H³ to depress the rod H² which, through the connections described, 65 shifts the locking plate C forwardly to in-

active position, this being the condition of the parts as shown in the drawing. On the other hand, when the switch-button is turned "off" to stop the operation of the motor, the cam plate H presents one of its elevations h¹ in engagement with the roller H¹, (see dotted lines in Fig. 2), thereby lifting the rod H² against the action of the spring H³ and shifting the locking plate rearwardly to active position. As the motor 70 constitutes the source of power for the entire machine, its stoppage necessarily involves the arrest of the operation of the keyboard rolls. In this connection, it is pointed out that my invention contemplates 75 the locking of the keyboard when the power driven means therefor are thrown out of action, whether this be accomplished independently or by shutting off the power for the entire machine as in the foregoing arrangement. 85

There may be times when the operator will wish to lock the finger keys against actuation without stopping the operation of the machine. This may be accomplished 90 simply by shifting the locking plate C rearwardly by hand, it being noted that the automatic actuating connections above described are such as to permit this independent manual control of the locking plate. 95 If desired, a rotary cam plate such as that disclosed in the parent application may be employed to facilitate the manual control of the locking plate.

While the improved locking device disclosed in the parent application has been made use of in the automatic arrangement above described, it should be understood that other locking devices might be employed with the same effect, my invention in 100 its broader aspects contemplating the automatic locking and unlocking of the keyboard under the conditions stated without regard to the particular form of locking device or of the connections between it and the motor. 105 As a matter of fact, in some aspects, my invention would be realized by the employment of a locking device which serves only to prevent or permit the release of matrices from the magazine. However, the use of the 110 improved locking device in the automatic arrangement presents many advantages and particularly in connection with a keyboard of the linotype class, wherein as before indicated the finger-keys control power-driven 115 elements which effect the release of the matrices. In short, I have herein shown my invention only in preferred form and by way of example and as applied to a particular kind of machine, but obviously many modifications and alterations therein and in its mode of application will suggest themselves to those skilled in the art without departing 120 from the scope of the invention. 125

Having thus described my invention, its 130

construction and mode of operation, what I claim is as follows:

1. In a typographical machine, the combination of a source of power, means for shutting off the power at will, a keyboard, locking means therefor, and means whereby the shutting off of the power automatically effects the locking of the keyboard.
2. In a typographical machine, the combination of an electric driving motor, a movable hand-switch controlling the operation of the motor, a keyboard, a movable locking plate therefor, and connections between the hand-switch and locking plate whereby the latter is moved to its active and inactive positions as the motor is stopped and started, respectively.
3. In a typographical machine, the combination of a keyboard, power-driven means therefor, means for throwing said power-driven means out of action at will, locking means for the keyboard, and means whereby said locking means are rendered active automatically as the power-driven means are thrown out of action.
4. In a typographical machine, the combination of a keyboard, power-driven means therefor, a manually operated device for throwing said power-driven means out of action, a movable locking plate associated with the keyboard, and connections between the manually operated device and locking plate whereby the latter is moved to its active and inactive positions as the power-driven means are thrown out of and into action, respectively.
5. In a linotype machine, the combination of a source of power, means for shutting off the power at will, locking means to prevent the release of matrices from the magazine, and means whereby the shutting off of the power automatically renders the locking means active.
6. In a typographical machine, the combination of a source of power, means for shutting off the power at will, a keyboard,

and means actuated automatically by the shutting off of the power to prevent the manipulation of the keyboard.

7. In a typographical machine, the combination of a keyboard presenting a series of finger keys, a locking plate formed with slots through which the forward ends of the finger keys extend and movable backwardly and forwardly to shift the end walls of its slots into and out of engagement with the finger keys so as to prevent or permit the actuation of the finger keys according to the position of the locking plate, power-driven means for the keyboard, means for throwing said power-driven means out of action at will, and means whereby the throw-out of the power-driven means effects the movement of the locking plate to active position.

8. In a typographical machine, the combination of a keyboard presenting a series of finger keys, a locking plate formed with slots through which the forward ends of the finger keys extend and movable backwardly and forwardly to shift the end walls of its slots into and out of engagement with the finger keys so as to prevent or permit the actuation of the finger keys according to the position of the locking plate, power-driven means for the keyboard, a manually operated device controlling the operation of said power-driven means, and connections between the manually operated device and the locking plate whereby the latter is moved to its active and inactive positions as the power-driven means are rendered inactive and active, respectively.

9. A combination as recited in claim 1, characterized by the fact that the keyboard locking means therein recited are also capable of independent manual operation so as to permit the finger keys to be locked or unlocked at will.

In testimony whereof, I have affixed my signature hereto.

DAVID S. KENNEDY.
